FREDA L. HANNUM, OF SEATTLE, WASHINGTON

CURTAIN DRIER AND STRETCHER

Application filed May 23, 1933. Serial No. 279,912.

My invention relates to improvements in curtain driers and stretchers and the object of my invention is to provide a new article of manufacture for use in home laundry work in the nature of a perforated cylinder or shell of simple and cheap construction which is adapted to have curtains and similar material wound thereon and dried whereby said curtains will be straight and smooth 10 when the drying process is finished.

Another object is to provide a perforated shell of this nature which has tape threaded therethrough both longitudinally and circumferentially to afford means to which the 15 curtains may be pinned or otherwise fastened.

Another object is to provide a curtain drying and stretching shell of this nature having one or more longitudinally corrugated end pieces preferably of expanding or conical 20 shape which are adapted to have the ruffles of the curtain drawn thereover so that they will impart a fluted shape to said ruffles during the drying process.

Another object is to provide a curtain drier 25 and stretcher of this nature which is made up of two or more telescopic sections adapted to form a drying and stretching tube when they are extended and to form a hamper or receptacle when they are telescoped.

Other and more specific objects will be 30 apparent from the following description taken in connection with the accompanying drawings.

In laundering curtains it is necessary to 35 stretch the curtains while they are drying so that they will dry smooth and straight and will not require ironing. In domestic or home laundry work this has heretofore been done by pinning the curtains out flat on 40 large rectangular frames. These frames cost a substantial amount, are cumbersome to handle, take up a great deal of room and ordinarily must be set up and taken down each time they are used. My present invention 45 overcomes the objections due to these frames by providing a curtain stretching and drying device of such cheap construction that it may be purchased by any person desiring to launder their own curtains and by providing 50 a curtain drier and stretcher which is

always ready for use, which does not have to be set up and taken down, which takes up very little room either when in use or when not in use, and which is efficient in drying curtains quickly and leaving the same 55 straight and smooth.

In the accompanying drawings Figure 1 is an elevation of a curtain drying and stretching device constructed in accordance with my invention.

Figs. 2 and 3 are cross sections of the same substantially on broken lines 2—2 and 3—3 respectively of Fig. 1.

Fig. 4 is a fragmentary view partly in longitudinal section and partly in elevation 65 showing a ruffle drier and shaper on the end of the main drying tube.

Fig. 5 is a fragmentary cross section on line 5—5 of Fig. 4 of said ruffle drier.

Fig. 6 is a longitudinal section of a curtain stretcher and drier made up of a plurality of telescopic sections the same being shown extended.

Fig. 7 is an elevation showing the telescopic drier telescoped or collapsed to form a hamper.

Like reference numerals designate like parts throughout the several views.

Referring to Figs. 1 to 5 inclusive the numeral 10 designates a relatively long tube 80 preferably constructed of card board or of similar cheap material. The tube 10 is preferably open at both ends and is provided with a plurality of perforations 11 whereby air for drying purposes may circulate freely 85 therethrough. The perforations 11 also serve as means through which circumferential and longitudinal strips or tapes 12 and 13 respectively of flexible material may be passed, said tapes being thus secured to the cylinder and 90 serving as means to which curtains 14 may be pinned or otherwise attached.

For the purpose of drying and stretching curtains with ruffles, I provide, on the end of the tube 10, an expanded or conical member 95 15 which is longitudinally corrugated or fluted as shown in Fig. 5, and is adapted to impart a fluted shape to any ruffle which is dried thereon. The conical ruffle drier may be rigidly secured to the tube 10 or it may be 100

detachable therefrom and said ruffle drier may be perforated and may have tapes threaded therethrough so that the ruffle may be pinned to the tapes.

5 In Figs. 6 and 7 I have shown a curtain drier and stretcher composed of two telescopic sections 16 and 17 perforated as at 18 and arranged to be extended as shown in Fig. 6 for drying purposes or to be telescoped, as shown 10 in Fig. 7, to form a hamper wherein dirty or damp towels, dirty clothes and the like may be placed. In this form of drier a perforated bottom 19 may be provided at one end and a ruffle drier 20 may be provided at the other 15 end, said ruffle drier serving as a funnel shaped mouth when the device is telescoped to form a hamper. When the telescopic parts 16 and 17 are extended they may be secured in the extended position by lacing a 20 tape 21 through the registering perforations of the overlapping portions of the same. The telescopic device is adjustable to curtains of different width or the two sections of the same may be taken apart and used independently of each other for short curtains if desired.

In the use of this curtain drier and stretcher one end of the wet curtain is preferably 25 first drawn out straight and pinned to the tape 13 which extends lengthwise of the tube and the curtain is then rolled or wound on the tube, the edges of the curtain being drawn or stretched out and pinned to the end tapes 12 as the winding proceeds, thus stretching 30 the curtain and holding the edges of the same straight. The tapes 12 form a guide for keeping the edges of the curtains straight and a means to which the edges of the curtains may be fastened and said tapes are 35 easily taken out and put in again so that they may be quickly and easily adjusted for curtains of different width.

40 After a damp curtain has been rolled on the tube it is allowed to dry thoroughly, and when it is removed it will be smooth and straight and free from wrinkles. The perforations insure a free circulation of air through the curtain and hasten the drying process. If the ruffle is caused to conform to 45 the fluted shape of the ruffle former it will retain this desired shape after the curtain is dried. The tube 10 does not need to be of large diameter and a curtain may overlap several times when it is wound on said tube 50 without seriously retarding the process of drying.

55 The foregoing description and accompanying drawings clearly disclose certain preferred embodiments of my invention, but it will be understood that this disclosure is merely illustrative and that such changes in construction may be made as are fairly within the scope and spirit of the following claims.

I claim:

1. A curtain stretcher and drier embodying a perforated shell, and strips of pliable material threaded through the perforations in said shell and forming means to which a 70 curtain may be secured.

2. A curtain stretcher and drier embodying a perforated tube and strips of pliable material threaded through the perforations in said tube and extending longitudinally 75 and circumferentially thereof.

3. A curtain stretcher and drier embodying a perforated tube and a corrugated ruffle drier section at the end of said tube.

4. A curtain stretcher and drier embodying a perforated tube and an expanded cone shaped, longitudinally corrugated ruffle drier connected with said tube. 80

5. Devices of the class described embodying a plurality of relatively telescopic perforated tubular sections arranged to be telescoped within each other to form a receptacle or to be extended to form a curtain drying tube and lacing strips of flexible material arranged to be laced through the registering perforations of said sections to secure said sections in extended position and to afford means to which the curtains may be fastened. 90

The foregoing specification signed at Seattle, Wash., this 14th day of May, 1928.
